UNITED STATES PATENT OFFICE

2,177,163

GARMENT HANGER

Leonard A. Young, Detroit, Mich.

Application October 13, 1938, Serial No. 234,756

2 Claims. (Cl. 223—88)

The main objects of my invention are:

First, to provide a garment hanger having provisions for effecting substantial economies in the cost of manufacturing the same.

Second, to provide a garment hanger having a wire yoke and hook formed partially of relatively light gauge stock without detracting from the strength of the hanger.

Further objects relating to details and economies of my invention will definitely appear from the description to follow. The invention is defined in the claims.

A structure embodying the features of my invention is illustrated in the accompanying drawing, wherein:

Fig. 1 is an elevation view of a garment hanger in accordance with my invention.

Fig. 2 is an enlarged fragmentary front perspective view illustrating details of the invention.

The present invention relates to a hanger similar in general to that shown and claimed in my copending application, Serial No. 234,755, filed October 13, 1938 in that it aims to reduce the cost of manufacture without detracting from the strength of the resultant article. For purposes of illustration, I have shown my invention in connection with a paper strut hanger, but it will be apparent that the inventive concept is not restricted in that particular.

Referring to the drawing, the reference numeral 1 in general indicates the hanger of my invention, which consists of a yoke 2 formed of wire and comprising a pair of downwardly diverging garment supporting arms 3, shoulders 4 integral with arms 3 at the apex thereof, and the terminal inwardly directed portions 5 at the other end thereof, which portions are provided with offset lugs 6 adapted to receive a tubular paper strut 7 thereon and frictionally engaging the interior of the strut whereby to hold the same in operative position.

Intermediate the shoulders 4, the yoke 2 is provided with an upwardly extending offset or bay 45 for the purpose of accommodating a hanger engaging element on a conveyor such as is employed in cleaners' establishments. This bay likewise serves as a point of attachment for the suspending hook member 9 of my hanger in the following manner. The said suspending member consists of a length of wire stock preferably of a gauge considerably lighter and preferably two or more gauges lighter than the stock of yoke 2. It is

folded at its middle to provide a pair of strands 10 terminating in shank members 11 which are wrapped around the opposite substantially vertically extending sides 12 of the offset or bay 8. The wrapped extremity of shank members 11 is indicated by the reference numeral 13. Shank members 11 serve as a shank for the hanger and the remainder of the suspending member 9 is conformed to provide a hook 15.

On account of the double strand construction 10 of suspending member 9, it is possible to form the same of substantially lighter stock than that of yoke 2, thereby effecting a substantial economy in material cost without diminishing the strength of the hanger. The strands 10 are preferably 15 spaced substantially in a direction perpendicular to the plane of yoke arms 3, whereby a convenient and comfortable grasp of the hanger is had for handling the same.

My improved form of hanger does away with 20 the extensive twisting commonly employed to provide the shank, thereby further reducing the cost of production, while the expedient of wrapping the shank members 11 about offset 8 is ample to prevent deformation or displacement of the 25 suspending member.

I have illustrated and described my improvements in an embodiment which is very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. A garment hanger comprising a yoke having a pair of downwardly diverging garment supporting arms and shoulders intermediate said arms, said yoke having an offset between said shoulders, and a hook and shank member including a length of stock bent on itself to provide double strands and having the ends thereof wrapped about the sides of said offset, the double strand member being conformed to provide a suspending hook.

2. A garment hanger comprising a yoke having downwardly diverging arms and an upward loop-like offset at the apex thereof, and a double strand hook having diverging shank members wrapped around the side portions of said upward offset of said yoke.

LEONARD A. YOUNG.
